UNITED STATES PATENT OFFICE.

HENRY GIBSON O'NEILL, OF NEW YORK, N. Y., ASSIGNOR OF ONE-HALF TO CONRAD HUBERT, OF NEW YORK, N. Y.

PRIMER FOR INTERNAL-COMBUSTION ENGINES.

1,201,086.

Specification of Letters Patent.

Patented Oct. 10, 1916.

Application filed May 15, 1913. Serial No. 767,783.

To all whom it may concern:

Be it known that I, HENRY GIBSON O'NEILL, a citizen of the United States, residing in the borough of Manhattan, city of New York, in the county of New York, 5 and State of New York, have invented certain new and useful Improvements in Primers for Internal-Combustion Engines, of which the following is a specification, reference being had therein to the accompanying drawings, forming part thereof.

My invention relates to priming devices for internal combustion engines, and particularly to that class of priming devices 15 which vaporizes the preliminary charge of fuel utilized in initiating the operation of the engine.

As is well known, difficulties are frequently had in the starting of internal combustion engines, due usually to the failure of the carburetor to produce a rich enough mixture as the engine is preliminarily turned over by hand or by some automatic device, and also to the inability to attain an explosive temperature of the charge of fuel introduced into the engine, particularly when the engine is cold. Various expedients have 20 been heretofore proposed to obviate these difficulties, such as introducing a priming charge of fuel into the cylinders of the engine, and it has been proposed to preheat and thereby to some extent vaporize the priming charge to facilitate ignition.

An object of my invention is to provide 35 a device of this sort which may be easily operated and will reliably and quickly heat and vaporize the priming charge, and which may conveniently be attached or adapted to any internal combustion engine either before or after its installation.

Other objects are convenience in the supplying of fuel to the device, simplicity and compactness of the construction and arrangement of the parts, and celerity and convenience in its operation.

Still other objects and advantages of my invention will appear from the following description.

In accordance with my invention I provide 50 a vaporizing device connected between the manifold or other intake passage of the engine and a suitable fuel supply, preferably the main fuel supply line, and preferably through a by-pass around the carburetor, this 55 vaporizing device including heating means

for heating and vaporizing the liquid fuel in the device, and means for controlling in common, as by a single actuation, the fuel supply of the vaporizer and the operation of the heating means.

My invention also comprehends, as a heating means or heat generator, an electric conductor, such as a resistance coil, and also a body of absorbent material for the fuel, such as asbestos wicking, combined with the heat generator to facilitate and expedite 60 the evaporation of the fuel under the influence of the heat.

My invention also comprehends various other features of construction and arrangement and combinations of parts, as will hereafter more fully appear.

I shall now describe the embodiment of my invention illustrated in the accompanying drawings, and shall thereafter point out 70 my invention in claims.

Figure 1 is a partial elevation and a partial diagram showing my improved vaporizer applied to a two cylinder internal combustion engine. Fig. 2 is a central vertical 80 elevation, on an enlarged scale, of the vaporizer.

My invention is particularly adapted for use on automobiles and other motor vehicles, boats or the like, employing internal combustion engines, though not necessarily limited to such use, and I shall hereafter describe it as so used.

In the illustrated embodiment of my invention, the vaporizer is connected between 90 the main gasoline or fuel supply pipe 1 and the manifold 2 of the engine, through a bypass or conduit around the carburetor 3, consisting of an inlet pipe 4, leading from the main supply pipe 1 to the vaporizing 95 receptacle 5, and an outlet pipe 6, leading from the vaporizer to the manifold 2 at the juncture of the two branches. The inlet pipe 4 is connected to a nipple 7 and communicates with the inlet opening therethrough, 100 which is disposed some distance above the bottom of the receptacle 5, whereby the bottom of the vaporizing chamber below the inlet opening serves as a reservoir in which a certain quantity of fuel collects and is retained until evaporated. The inner end of the inlet opening is made flaring and serves as a valve seat for a normally closed conical valve, as will hereafter appear. The outlet pipe 6 is coupled to a hollow screw plug 105 110

8 which is screwed into an opening near the top of the receptacle 5, and the outlet opening is protected by a screen 9 disposed across the opening. It will be noted that, 5 with this arrangement of the vaporizer, fuel is drawn from a single source of supply through both the vaporizer and carbureter when the valve controlling the branch conduit is open, into the manifold of the engine 10 as the engine is turned over, it only being necessary to open the valve to permit the engine to draw fuel through both of these passages.

The fuel which is drawn through the vaporizer is evaporated by heat, which is turned on at the same time that the valve is opened and by the same operation as will now be described. The controlling valve is incorporated into the structure of the vaporizer and is internally arranged, the seat of the valve being formed about the inlet opening to the vaporizing chamber. A conical valve head 10 is formed on the inner end of an actuating stem 11 which projects outside of the casing or receptacle 5 and is guided through a stuffing box 12 threaded into the casing in alinement with the inlet opening in the nipple 7. The valve head 10 is normally held seated in the valve seat at the inner end of the inlet opening by the pressure of a coiled spring 13 which surrounds the stem 11 within the vaporizing chamber and bears at one end against the inner end of the stuffing box 12, and at its 30 other end against a head 14 on the valve stem just back of the valve head 10. The valve is opened by an outward pull on the valve stem against the tension of the spring 13.

As a heating agent an electrical resistance coil 15 is provided in the vaporizing chamber. This is carried by a removable closure or stopper 16 for the vaporizing chamber, which is composed of suitable insulating material, such as bakelite. The resistance coil 15 is held distended by a plate 17 of insulating material carried by the stopper, which plate extends down nearly to the valve stem 11, and has a perforation near its lower end through which the coil 15 extends. The resistance coil is secured at its two ends to contact screws 18 which extend up through the stopper 16, and the two electrical leads 19 and 20 are secured by binding screws to the upper projecting ends of the contact screws 18.

The two leads 19 and 20 are insulated and pass down through an opening 21 in the stopper 16 and thence downwardly through a longitudinal opening 22 in the wall of the receptacle, the stopper 16 being inserted with the two openings in alinement. The opening 22 terminates at its lower end in an open slot 23 in the side of the receptacle, over which is secured an insulating plate 24 carrying two stationary electrical contacts

25 and 26, the upper and lower ends of the slot 23 being left uncovered by the plate 24. The lead 19 is brought out above the plate 24 and is secured to the stationary contact 25, and a wire 27 is secured to the other contact 70 26, and extends thence to one pole of the battery 28 or other source of electrical energy, while the lead 20 is brought out below the plate 24 and extends to the other pole of the battery 28.

To connect the two contacts 25 and 26 together and thus close the electric circuit for the resistance coil 15, a movable contact member 29 is provided, which is carried on the inner end of an upwardly and inwardly 80 projecting arm 30 on the outer end of the valve stem 11, and the movable contact 29 is so arranged that it will make contact with the two stationary contacts 25 and 26 as it is moved outwardly, and will normally be held 85 inwardly out of contact making position by the spring 13. The contacts are of any suitable form, such as the well known knife blade contacts. It is now apparent that the electric circuit is closed and the valve is 90 opened by the outward movement of the valve stem 11. This may be effected by a cord 31 which leads to any convenient place for manual control, as to the dash board of the automobile, though it is manifest that 95 any suitable means of control may be provided.

To facilitate the evaporation of the liquid fuel in the vaporizer, suitable absorbent material, such as asbestos wicking 32, is provided about the coil 15 and extends down into the reservoir portion at the bottom of the vaporizing chamber, and by capillary attraction becomes thoroughly moistened with the liquid fuel. When the electric circuit is closed and the coil becomes heated, 100 this fuel in the absorbent material is very quickly evaporated and passes through the outlet pipe 6 and enters the manifold 2, whence it is drawn into the cylinders of the 105 engine as the inlet valves are opened and the engine is turned over. This vapor mingles with the air which is at the same time drawn through the carbureter and, being hot, is readily ignited. It will be noted that the 110 wicking 32 will be kept moist by fuel in the reservoir portion of the vaporizing chamber. Usually it will only be necessary to hold the vaporizer inlet valve open for a brief starting period of the engine.

The stopper 16 is secured in place by a screw cap 33 which has a shoulder portion clamping down on a shouldered portion of the stopper overlying the top of the casing 5 of the vaporizer, the screw cap 32 having a 115 screw-threaded enlarged lower portion which fits over and engages the screw-threaded top portion of the casing 5.

It is obvious that various modifications may be made in the construction shown and 130

above particularly described within the principle and scope of my invention.

I claim:

1. A primer for an internal combustion engine, such primer comprising a vaporizing chamber, means for supplying liquid fuel to such chamber, a fuel absorbent in the vaporizing chamber a vapor conduit forming an outlet from the vaporizing chamber and adapted to be connected to the intake passage of the engine, means for heating the contents of the vaporizing chamber, and manually controlled means in common in control of the heating means and of the fuel supply means.

2. A primer for an internal combustion engine, such primer comprising a vaporizing chamber, means for supplying liquid fuel to the vaporizing chamber, a fuel absorbent in the vaporizing chamber a vapor-conveying outlet conduit for the vaporizing chamber adapted to be connected to the intake passage of the engine, an electrical heater for the vaporizing chamber, and manually controlled means in common in control of such heater and the fuel supply means for rendering such heater operative only during the time that the fuel is being supplied to the vaporizing chamber.

3. A primer for internal combustion engines comprising a fuel supply, a conduit leading from the fuel supply to an intake passage of the engine, a vaporizing chamber in the conduit, an electrical heating conductor in the vaporizing chamber, a fuel absorbent body disposed in the chamber in proximity to the conductor, a normally disconnected source of electric current for the conductor, a valve normally closing the conduit, and means actuatable to open the valve and to connect the source of current to the conductor.

4. A primer for an internal combustion engine, such primer comprising a vaporizing chamber, means for supplying liquid fuel to such chamber including a fuel supply conduit forming a fuel inlet and a valve in control thereof, a vapor-conveying outlet conduit from such chamber adapted to be connected to the intake passage of the engine, electrical heating means within the vaporizing chamber, a fuel absorbent in the vaporizing chamber in proximity to such heating means, a circuit controller for such heating means, and manually controlled means in common for concurrently opening the fuel supply valve and closing the electric circuit of the heating means or vice versa.

5. A primer for an internal combustion engine, such primer comprising a vaporizing chamber, a fuel inlet conduit for fuel liquid opening into such chamber above the bottom thereof for forming a reservoir for fuel liquid in such chamber below such fuel

inlet, a fuel absorbent in the chamber and extending both above and below the fuel inlet, a conduit forming a vapor outlet above the fuel inlet and adapted to be connected to the intake passage of the engine, and means for heating the contents of the vaporizing chamber.

6. A primer for an internal combustion engine, such primer comprising a vaporizing chamber having a movable end closure of electrically insulating material, means for supplying fuel liquid to the vaporizing chamber, a vapor-conveying outlet conduit for such chamber adapted to be connected to the intake passage of the engine, conductive supporting stems passing through the end closure, and a U-shaped electrical heating coil mounted at its ends by means of said conductive supporting stems upon said insulative end closure and projecting at its middle within the chamber.

7. A primer for internal combustion engines comprising a vaporizing chamber having a fuel inlet adapted to be connected to a source of fuel supply and having a fuel outlet adapted to be connected to the intake passage of the engine, an electrical heating device for the vaporizing chamber, a fuel absorbent in the chamber and subjected to the heat of the heating device, a valve in control of the fuel supply to the vaporizing chamber, a circuit controller for the heating device adapted to control current therefor, and means for causing the fuel valve to operate jointly with the circuit controller so that the valve will be opened when the heating device is supplied with current and so that this valve will be closed when the current supply to the heating device is discontinued.

8. A primer for an internal combustion engine, such primer comprising a conductive receptacle part forming the body of a vaporizing chamber, a stopper of insulating material removably fitting into the receptacle part and forming a removable cover therefor, a cap for clamping the stopper in place on the body, conductive supporting stems passing through the stopper in insulated relation to each other, a U-shaped electrical heating coil supported at its ends by the conductive stems upon the stopper, means for supplying fuel liquid to the vaporizing chamber, and a vapor conveying outlet conduit for such chamber adapted to be connected to the intake passage of the internal combustion engine.

9. A primer for an internal combustion engine, such primer comprising a conductive receptacle part forming the body of a vaporizing chamber, a stopper of insulating material removably fitting into the receptacle part and forming a removable cover therefor, a cap for clamping the stopper in place on the body, conductive supporting stems

passing through the stopper in insulated relation to each other, a U-shaped electrical heating coil supported at its ends by the conductive stems upon the stopper, a fuel absorbent in the body of the vaporizing chamber in proximity to and surrounding the heating coil, means for supplying fuel liquid to the vaporizing chamber, manually controlled means in common in control of the fuel supply and the heating coil, and a

vapor conveying outlet conduit for such chamber adapted to be connected to the intake passage of the internal combustion engine.

In testimony whereof I have affixed my ¹⁵ signature in presence of two witnesses.

HENRY GIBSON O'NEILL.
